UNITED STATES PATENT OFFICE.

ZION E. FIVEASH AND CHARLIE B. LEONARD, OF RAWLES SPRINGS, MISSISSIPPI.

WOOD-DISTILLING APPARATUS.

No. 890,418.

Specification of Letters Patent.

Patented June 9, 1908.

Application filed December 26, 1905. Serial No. 293,366.

To all whom it may concern:

Be it known that we, ZION E. FIVEASH and CHARLIE B. LEONARD, citizens of the United States, residing at Rawles Springs, in the 5 county of Perry and State of Mississippi, have invented a new and useful Wood-Distilling Apparatus, of which the following is a specification.

This invention relates to means for extracting the various well known products, such as creosote, turpentine, and the like from wood.

The object is to provide an apparatus that is comparatively simple in structure, is entirely efficient for the purposes intended, and is very convenient to operate.

The preferred form of structure is illustrated in the accompanying drawings, wherein:

20 Figure 1 is a side elevation of the apparatus. Fig. 2 is a vertical longitudinal sectional view therethrough. Fig. 3 is a front elevation of the chute and a portion of the conveyer, parts thereof being broken away 25 and shown in section. Fig. 4 is a front elevation of the lower portion of the retort chamber and the conveyer, portions of the latter being broken away. Fig. 5 is a detail sectional view through the lower door.

30 Similar reference numerals designate corresponding parts in all the figures of the drawings.

In the embodiment illustrated, a supporting structure is employed comprising a frame 35 35 6, on which is supported a retort chamber 7, comprising a cylindrical body 8, located at an inclination and having heads 9, constituting the end walls of the chamber. Saddle brackets 10, secured to the cylinder and resting 40 on the supporting frame, serve to maintain the chamber in proper position. The heads 9 are disposed in angular relation, so that the lower one will assume a more nearly vertical position and the upper one will be 45 disposed in more nearly a horizontal plane. The upper head is provided with an inlet opening or doorway 11, and the lower head has a corresponding outlet opening or doorway 12. These openings or doorways are 50 arranged to be closed by swinging doors 13, hinged at their upper edges, as shown at 14, to the heads, and carrying ears 15 at their lower ends, which ears are arranged to be engaged by stud bolts 16, carried by the heads, said stud bolts receiving holding nuts 55 17, that engage over the ears. Suitable lead

or other gaskets 18 are employed to obtain tight joints about the doorways when the doors are in closed position.

For the purpose of heating the chamber 60 and the contents thereof, a steam pipe 19, leading from any suitable source of supply, has connection with a heater pipe extending longitudinally within the lower portion of the retort chamber, said supply pipe having 65 a controlling valve 20. The heater pipe comprises sections 21 and 22, connected by a coupling 23. The upper section 21 is imperforate, while the lower section 22 is provided with suitable perforations, constituting 70 outlets for the steam. This lower section 22, furthermore, preferably projects through the lower head of the chamber and is closed by a cap 24. A distillate conducting pipe 25 is connected to the upper end of 75 the chamber and has a controlling valve 26. This pipe 25 is connected to a condenser coil 27, arranged within a tank 28, which coil projects from the tank and is provided with a discharge nozzle 29, having a dip 30. A gas 80 vent 31 is connected to the nozzle in advance of the dip 30, and said nozzle delivers to a suitable receptacle, as 32, which receptacle is provided with a siphon 33, connected to the lower portion thereof and having a 85 vent 34.

Means are provided for supplying the chamber with material. In the present embodiment, a chute body 35 is mounted on a suitable supporting frame 36 and has a bottom 37, that inclines downwardly toward the inlet opening 11 of the chamber. The vertical wall 38 of the chute body that is disposed adjacent to the upper end of the retort chamber has a discharge opening 39, 95 located in line with the doorway 11. A gate 40, hinged, as shown at 41, to the vertical wall 38, controls the discharge and is adapted to be maintained in closed position by turn buttons 42. A conveyer leads from the mill 100 or other apparatus at which the material is prepared. Said conveyer comprises a trough 43, leading over the top of the chute and having an opening 41, in its bottom, communicating with the interior of said chute. 105 An endless chain 45, operates longitudinally in the trough and is provided with spaced cross slats 46, that are disposed transversely of the trough. A similar refuse conveyer cooperates with the lower discharge opening or 110 doorway 12 of the retort chamber to remove the refuse from the vicinity thereof. This

conveyer consists of a trough 47, in which operates an endless chain 48, having crossed slats 49, disposed transversely of the trough. The latter conveyer leads to any suitable point of discharge.

The material is preferably, in the form of sawdust, chips, or similar small pieces, being brought to the apparatus by the conveyer chain 45 and the crossed slats and deposited in the chute. When it is desired to charge the retort chamber, the upper door is opened and the material is allowed to pass from the chute into the chamber. When sufficient material is collected therein the upper door is closed, and steam is admitted to the chamber through the pipe 19, and the sections 21 and 22. The pressure of the steam within the chamber can be ascertained by means of a suitable gage 50, connected to the upper end of the chamber. The products, in the form of vapor, will pass off through the pipe 25 and will be condensed in the coils 27, escaping through the nozzles 29 in the receptacle 32. By having the upper portion of the steam supply pipe imperforate, and the lower portion perforate, it will be apparent that the steam escaping from said pipe must necessarily pass through practically the entire body of the material within the retort chamber, before it escapes through the pipe 25, and thus the full body of material will be properly treated. The water, collecting at the bottom, may be drawn off through the siphon 33, thus leaving the desired distillates in the receptacle. To remove the refuse, it is only necessary to open the lower door 13, whereupon the same will be discharged into the lower conveyer and be carried thereby away from the vicinity of the apparatus. It will be apparent that this structure is simple and convenient to operate. Moreover, it will perform the functions desired with efficiency and expedition.

From the foregoing it is thought that the construction, operation, and many advantages of the herein described invention will be apparent to those skilled in the art, without further description, and it will be understood that various changes in the size, shape, proportion, and minor details of construction may be resorted to without departing from the spirit or sacrificing any of the advantages of the invention.

Having thus described our invention what we claim as new and desire to secure by Letters Patent, is:

1. In a still of the character described, the combination with a retort chamber, of means for feeding material thereto, said means including a chute located above the chamber and a conveyer delivering to the chute, said conveyer comprising a trough having in-

clined sides located over said chute and having an open bottom that communicates with the chute, and a conveyer flight moving in the trough over the open bottom but exceeding the width of said bottom.

2. In a still of the character described, the combination with a retort chamber set at an inclination and having a discharge opening in its lower end, of means for feeding material to the upper end of the chamber, and means for conveying the refuse from the lower end of the chamber, said latter means comprising a trough located exteriorly of the chamber and receiving the material directly from the discharge opening, and an endless flight operating in the trough and including scraper slats disposed transversely of and operating through the trough.

3. In a still of the character described, the combination with a retort chamber, of a steam conducting heater pipe extending longitudinally within the same and comprising upper and lower sections, the upper section being imperforate and the lower section having perforations, and a distillate conducting pipe connected to the upper portion of the chamber.

4. In a still of the character described, the combination with a retort chamber disposed at an inclination and having an upper supply inlet and a lower refuse discharge, of closures for said inlet and discharge, a heater pipe extending within the chamber longitudinally along the lower side thereof and having its lower portion perforate, said pipe being disposed below the inlet and discharge, and a distillate conducting pipe communicating with the upper portion of the chamber.

5. In a still of the character described, the combination with a retort chamber disposed at an inclination and having an upper supply inlet and a lower refuse discharge, of means for supplying material to the chamber through the upper inlet, said means including a conveyer, a refuse conveyer disposed exteriorly of the chamber below the discharge, a heater pipe extending longitudinally through the chamber along the lower side thereof and through the end walls beneath the inlet and discharge, said heater pipe having its lower portion perforate and its upper portion imperforate, and a distillate conducting pipe communicating with the upper portion of the chamber.

In testimony, that we claim the foregoing as our own, we have hereto affixed our signatures in the presence of two witnesses.
